UNITED STATES PATENT OFFICE.

GUSTAVE VICTOR HUGO, OF LOS ANGELES, CALIFORNIA.

THERMOCHROMATIC BALL-BEARING MASSAGE INSTRUMENT.

1,283,777.

Specification of Letters Patent. Patented Nov. 5, 1918.

Application filed January 21, 1918. Serial No. 212,863.

To all whom it may concern:

Be it known that I, GUSTAVE VICTOR HUGO, a citizen of the United States, residing at Los Angeles, in the county of Los Angeles, 5 State of California, have invented new and useful Improvements in Thermochromatic Ball-Bearing Massage Instruments, of which the following is a specification.

This invention relates to therapeutic medical massage devices; and it has as its object the provision of a massage instrument by the use of which combined mechanical and medical therapeutic operations may be made in an efficient manner.

15 My instrument, in its preferred and most full form, embodies in combination means for mechanical massage action and also means for heat and light action, with means provided for applying light of different colors to the body part being subjected to the action of the instrument. The instrument also embodies certain mechanical arrangements and appliances which are hereinafter described. Its essential feature 20 is the use of ball bearings and mechanical massaging elements; and when I speak of any instrument as combining the other features mentioned herein, I do not mean that such features must be used.

30 My invention will be best understood from the following detailed description of a preferred form of instrument, reference being had for this purpose to the accompanying drawings in which—

35 Figure 1 is a side elevation of the instrument; Fig. 2 is a plan thereof; Fig. 3 is a longitudinal central section showing the construction of the instrument; and Fig. 4 is a reduced side elevation of the complete instrument showing the straps by which it may be manipulated if desired.

In the drawings I illustrate an instrument which, in its most full form, preferably includes a shell 10, made in the form of a reflector, and having its inner surface polished or otherwise rendered reflective, and adapted to contain an electric lamp 11, mounted in socket 12. The socket 12 is held in a handle socket 13 arranged with a clamping strap 14 in which is clamped a tube or nipple 15 extending from the shell 10 and formed solidly with the shell. One handle 16 of the

device is mounted upon the handle socket 13, while the other handle 17 of the device is mounted upon a bracket 18 which is secured to the shell 10, or to a bracing frame work 19 mounted upon the shell. The shell 10 is held to the base plate 20 of the instrument by means of thumb nuts 21 which hold the outer ends of this frame work 19 to the base plate 20. At the top or back of shell 10 another handle 22 is provided mounted upon frame work 19. Base plate 20 may be of any size and configuration. In the form of instrument shown the shell 10 is preferably circular; although it may be of any desired configuration. For instance, it may be elongated or oval. The base plate 20 may correspondingly be of any size and configuration; but it is preferably oval and of the shape shown in the drawings. It may be made in any shape to suit any particular use, for the limbs, the face, the body. In fact my device is capable of being made 75 for any and all massaging uses. On its under side and around its periphery there projects a plurality of ball bearings 25 mounted in sockets or cages 26. These sockets or cages may be of any suitable construction allowing the balls 25 to rotate freely in all directions. The balls 25 preferably project from the sockets a suitable distance so that, when the balls are in engagement with the body, the sockets will not come into forcible contact with the body. They need not be further explained here except that the balls are free to rotate when in contact with the body. The balls form the actual mechanical massaging members 90 and roll over the body surface, producing massaging and pressure effects without producing frictional effects.

The base plate 20 has a central preferably rectangular opening within the surrounding line of ball bearings and under the reflector shell 10. This opening is formed within an upwardly extending and surrounding flange 30. Shell 10 carries a transparency 31 held in a holder 32 at one end and in a spring clip 33 at the other end; this transparency covering the aperture within the flange 30. When the device is assembled the transparency 31 lies close to the edge of flange 30. Transparency 31 may be formed of 105

any suitably colored glass; or of any material having any desired specific properties of transmitting any particular kind of light or heat waves; so that all of the light, or 5 heat, which passes through the opening in the base plate may be colored or otherwise controlled in its characteristics thus being within the control of the operator who may substitute different transparencies. The 10 nature of the heat as well as the light transmitted to the body through the flanged opening may thus be varied by placing different transparencies in the holder. In fact, my instrument may be adapted, in form and in 15 control of the heat and light to the condition of the patient and to the treatment it is desired to effect.

I do not limit myself to the particular structures herein shown, various variations 20 may be made within the scope of my invention as will be understood from this description. For instance, more than a single line of ball bearings may be used. I illustrate, for example, an extra ball 25^a mounted 25 in a socket 26^a, within the outer line of balls 25.

Electric current is fed to the lamp 11 through the socket 12 and through a cord 35 which may extend out through the 30 handle 16. When the instrument is being applied by a masseur, the handles 16, 17 and 22 may be used in applying the instrument, as is most convenient for any particular kind of operation. The handles 16 35 and 17 may be provided with links or other means, as shown at 36, to which straps 37 may be connected; and by the use of these straps a person may manipulate the instrument upon his own body, the straps being 40 especially useful in applying the instrument to the back. Within the variations of my invention, the lamp may be omitted and an instrument may be made and used which embodies the mechanical features of the invention, with its various mechanical appurtenances, as set forth, using the instrument 45 for mechanical massaging purposes only.

My invention now having been made apparent by a description of a preferred form 50 thereof, it will be seen that various modifications and variations may be made without departing from the invention; and I reserve to myself such changes and modifications as may be made by persons skilled in the art 55 or which may fall within the scope of the following claims.

What I claim is:

1. A massage instrument, embodying in 60 combination a base plate, a plurality of physical massaging members mounted around the periphery of said base plate and comprising freely revoluble balls adapted to be manipulated in contact with the body;

a reflector shell removably mounted on the back side of the base plate, a pair of handles 65 mounted upon said reflector shell and extending in opposite directions parallel to the plane of the base plate, an electric lamp mounted in the reflector shell, the base plate having an opening opposite the lamp, and 70 a removable transparency held over said opening.

2. A massage instrument, embodying in combination a base plate, a plurality of physical massaging members mounted around 75 the periphery of said base plate and comprising freely revoluble balls adapted to be manipulated in contact with the body; a reflector shell removably mounted on the back side of the base plate, a pair of 80 handles mounted upon said reflector shell and extending in opposite directions parallel to the plane of the base plate, an electric lamp mounted in the reflector shell, a third handle mounted upon the shell at 85 its back side and projecting perpendicularly to the plane of the base plate, the base plate having an opening opposite the lamp and a removable transparency held over said opening. 90

3. A massage instrument, comprising in combination a base plate, a plurality of mechanical massage elements mounted upon and projecting from the front face of said base plate, being arranged on the base plate 95 in a row around the periphery of the plate, and embodying freely revoluble balls adapted to be brought into contact with the patient's body, the plate having a central opening within the row of massaging members; a reflector shell removably mounted upon the outside of the base plate, a removable and replaceable chromatic transparency held in the reflector over the opening in the base plate, a pair of handles 100 mounted upon said shell and projecting oppositely therefrom in a plane parallel to the plane of the base plate, a lamp socket carried by one of said handles, a lamp mounted in said socket and projecting into 110 the reflector shell and lying over the chromatic transparency and the opening in the base plate, means to supply electric current to said lamp embodying wires extending through said handle, and a third handle 115 mounted upon said reflector shell at its back and projecting perpendicularly to the plane of the base plate.

4. A massage instrument, embodying in combination a base plate with a central 120 opening, a plurality of physical massaging members mounted in a line around the periphery of the base plate around the opening therein and adapted to be manipulated in contact with the body, a reflector 125 shell on the back side of the base plate over

the opening, and an electric lamp in the reflector shell, from which lamp heat and light are radiated through the opening onto that portion of the body within the peripheral line of massaging members.

In witness that I claim the foregoing I

have hereunto subscribed by name this 11 day of January, 1918.

GUSTAVE VICTOR HUGO.
